BRACKET FOR BATHROOM FIXTURES

Paul F. Simpson, Washington, Conn., assignor to
The Autoyre Company, Oakville, Conn., a cor-
poration of Connecticut

Application February 15, 1954, Serial No. 29,041

Term of patent 14 years

(Cl. D4—3)

To all whom it may concern:

Be it known that I, Paul F. Simpson, a citizen of the United States of America residing in Washington, county of Litchfield, and State of Connecticut, have invented a new, original, and ornamental Design for a Bracket for Bathroom Fixtures, of which the following is a specification, reference being had to the accompanying drawing, forming a part thereof.

In the drawing illustrating my new design:

Fig. 1 is a plan view of a bracket for bathroom fixtures showing my new design;

Fig. 2 is a side view of the bracket of Fig. 1, and

Fig. 3 is an end view of the bracket of Fig. 1.

The dominant features of my new design have been illustrated in the drawing in full lines.

I claim:

The ornamental design for a bracket for bathroom fixtures, substantially as shown and described.
